CLAIM

The ornamental design for an automotive center console arm rest cover, as shown and described.

DESCRIPTION

FIG. 1 is a top, front and left-side perspective view of an automotive center console arm rest cover embodying my new design;

FIG. 2 is a rear elevational view thereof, the front elevational view being a mirror image;

FIG. 3 is a right-side elevational view thereof, the left-side elevational view being a mirror image;

FIG. 4 is a top plan view thereof; and,

FIG. 5 is a bottom plan view thereof.
